(57) **CLAIM**

The ornamental design for a push-pull rattle toy, as shown and described.

DESCRIPTION

FIG. 1 is a top view of the push-pull rattle toy;
FIG. 2 is a bottom view of the push-pull rattle toy;
FIG. 3 is a front view of the push-pull rattle toy;
FIG. 4 is a side view of the push-pull rattle toy; and,
FIG. 5 is a perspective view of the push-pull rattle toy.
The handle is shown partially broken away to indicate indeterminate length.

The portions shown in broken lines are for illustrative purposes only; and form no part of the claimed design.
